MEANS FOR CONTROLLING REFRIGERATING APPARATUS AND INTERCHANGING THE FUNCTIONS OF COMPLEMENTARY HEAT EXCHANGE ELEMENTS THEREOF

William V. Duke, Philadelphia, Pa., assignor to Baldwin-Southwark Corporation, a corporation of Delaware

Application May 31, 1933, Serial No. 673,758

11 Claims. (Cl. 62—4)

This invention relates generally to air conditioning apparatus of the type employing a compressor-condenser-expander circuit and more particularly to improved means for controlling the compressor automatically in accordance with a predetermined operation of suitable valve mechanism for interchanging the functions of the condenser and evaporator whereby the refrigerating system may be used for heating or cooling purposes.

Air conditioning apparatus especially of the room unit type employing complementary heat exchange elements over which outside air and room air are circulated respectively, may be effectively used for either heating or cooling the air of rooms, offices or the like merely by causing the heat exchange element within the flow of room air to serve alternatively as a condenser or evaporator.

To effect such interchange of functions, it is desirable to control the compressor in such a manner that refrigerant will not be pumped through the heat exchange elements during the interchanging operation thereof. In the specific embodiment of the invention herein shown the compressor is controlled by connecting or disconnecting the electric circuit to the compressor motor automatically in accordance with the initiation or completion of the interchanging operation or substantially so.

It is one object of my invention to provide improved means for controlling the compressor. Another object is to provide an improved switch mechanism and operating means therefor in conjunction with interchanging valve mechanism whereby the compressor will be rendered inoperative for pumping substantially upon initiation of the interchanging function and will have its pumping operation reestablished automatically substantially upon completion of the interchanging operation.

A further and more specific object is to provide a relatively simple, compact and economical construction and arrangement of rotatable switch means and actuating means therefor in conjunction with interchanging valve mechanism.

Other objects and advantages will be more apparent to those skilled in the art from the following description of the accompanying drawings in which:

Fig. 1 is a perspective looking up toward the under side of interchanging valve mechanism with my improved switching means and actuating mechanism therefor, the interchanging valves be-

ing shown with their valve stems projecting downwardly;

Fig. 2 is an elevational view of part of the interchanging valve mechanism with my improved compressor switch control embodied therewith;

Fig. 3 is a transverse section taken on line 3—3 of Fig. 2;

Fig. 4 is a diagram of the refrigerating system, interchanging valve mechanism and compressor switch control.

In the illustrated embodiment of the invention which is shown herein merely for purposes of disclosing one specific form among possible others that the invention might take, I have provided a refrigerating circuit including a motor 1 for driving a compressor 2 whose discharge side is connected to a pipe 3, thence through a passage 4 of interchanging valve 5 to pipe 6 and heat exchange element 7 over which outside air is preferably circulated to condense the refrigerant in this particular setting of the interchanging valves. Condensed refrigerant then flows through suitable traps or expansion valves 8 and 9 to a flooded type evaporator 10 over which room air is circulated to be cooled. The gaseous refrigerant from heat exchange element 10 then flows through pipe 11 to passage 12 of interchanging valve 13 and thence to the suction pipe 14 of the compressor. The refrigerant system so far described is employed preferably in an air conditioning unit of the type shown in the pending application of H. L. Galson, filed December 24, 1932, Serial No. 648,772. The interchanging valve mechanism and operating means therefor is preferably of the type disclosed in application of J. Vogler about to be filed or filed herewith. Hence it will suffice to describe the valve mechanism and operating means only briefly.

The interchanging valves, preferably of the rotatable type, are disposed preferably in an inverted position with the valve stems extending downwardly from the valve casings. Valve arms 15 and 16 preferably have slidable and pivotal connection as at 17 and 18 to right and left hand threaded nuts 19 and 20 respectively. An actuating screw shaft 21, upon which said nuts are threaded, is supported in suitable brackets 22 and 23 while the screw shaft is provided with a suitable slotted end 24. The operation of this valve mechanism consists in inserting a suitable crank in the slotted end 24 of the screw shaft 21 and rotating the same in the desired direction, it being noted that in one extreme position as shown in Fig. 1 the valve arms and nuts 19 and 20 are adjacent each other whereas upon suitable rota-

tion of the screw, these arms and nuts will be moved away from each other to the extreme ends of the screw, thereby rotating the valves and changing the valve ports 4 and 12, Fig. 4, to connect pipes 3 and 11 and 6 and 14 respectively to cause heat exchange element 7 to now function as an evaporator and element 10 as a condenser, thereby causing room air to be heated when flowing over condenser 10.

10 To permit the foregoing interchanging function to be effectively made without the possibility of injury to the refrigerating system or machinery thereof, I have provided in conjunction with the valve mechanism, a relatively simple switching mechanism and operating means therefor, whereby the compressor is rendered inoperative to perform its pumping mechanism, specifically by disconnecting the compressor motor. This switching mechanism includes a pin 25 secured to one of the screw nuts such as 20. Journalled upon a suitably reduced end of pin 25 is an insulation disc 26 upon which is mounted preferably two mercury switches 27 and 28 whose tubular glass containers are held by metal clips 29 and 30. These slips are suitably supported on an L-shaped metal frame 33 which is bent around the outer end of pin 25, the metal frame 33 being supported on the disc 26 by flanges 31 and 32 formed from and bent at right angles to frame 33. Terminals 34 and 35 are also secured to insulation disc 26 and wires 36 and 37 each connect into the contact-making ends 38 and 39 of switches 27 and 28. In the position shown in Fig. 2, switch 27 is in position to have the globule of mercury 39 make contact between wires 36 and 37 while the globule of mercury 40 in switch 28 is at the opposite end of its tube to break its contact.

To support and actuate the bracket 33 on disc 26 and also to insure simple and yet accurate alignment and positioning of the switches, the flanges 31 and 32 are provided with holes 41 and 42 adapted to be placed in alignment with corresponding holes in disc 26 and also in alignment with holes in an actuating arm 43. With said respective sets of holes in alignment, pins or rivets 44 may then be inserted to hold the various members and actuating arm 43 in fixed relation. A slot 45 in arm 43 receives a fixed pin 46 carried preferably by the housing of valve mechanism 13. The slotted end of the arm is preferably removably held by suitable means such, for instance, as a cotter pin 47 passing through pin 46, while disc 26 is held to pin 25 preferably by a cotter pin 48. If desired a suitable switch cover 49 may be detachably secured to disc 26. Terminals 34 and 35 are connected to a suitable relay 50 for controlling a motor circuit switch 51.

Operation.—To interchange the functions of the heat exchange elements 7 and 10, screw 21 is rotated thereby causing nuts 19 and 20 in their position shown in Fig. 1 to be moved away from each other, thereby causing valves 5 and 13, Fig. 4, to be rotated. Substantially immediately, although not necessarily, upon movement of nut 20, pin 25 will move therewith and accordingly cause rotation of disc 26 due to the outer end of arm 43 being guided around fixed pin 46. As disc 26 rotates from the position shown in Fig. 1 to that shown in Fig. 2, there is an intermediate position during which the pools of mercury 39 and 40 will each be in the non-contact end of their tubes with the result that no circuit is completed for relay coil 50, thus allowing motor circuit 51 to open to stop operation of the motor and com-

pressor. This double non-contact position occurs substantially early in the movement of nut 20 so that there is a substantial extent of adjustment of the interchanging valves 5 and 13 with the compressor inactive and before switch 27 is moved to a horizontal position such as shown in Fig. 2, where mercury 39 establishes contact between wires 36 and 37 at the contacting end 38. When this occurs, relay coil 50 is energized and switch 51 closed to restart the motor. By this time, however, the interchanging function has been substantially completed if not completed and hence the whole system is ready for operation. When it is desired to interchange the functions of the heat exchange elements in the reverse order, screw shaft 21 is merely rotated in the opposite direction to bring nuts 19 and 20 of the valve arms 15 and 16 to the position shown in Fig. 1 in which event switch 28 is rotated to a horizontal position as shown in Fig. 1, thereby to make contact between wires 36 and 37 at the end 39.

From the foregoing description it is seen that I have provided a relatively simple and yet highly effective means for controlling the compressor, this means being readily replaceable and adapted to be built as a unit for simple association and cooperation with the interchanging valve mechanism.

It will of course be understood by those skilled in the art that various changes may be made in the details of construction and arrangement of parts without departing from the spirit of the invention as set forth in the appended claims.

I claim:

1. Apparatus for controlling a refrigerating system having complementary heat exchange elements and a compressor comprising, in combination, valve means for interchanging the functions of said heat exchange elements, means rotatable about a single axis for rendering said compressor inoperative automatically substantially upon initiation of said interchanging operation, said latter means including a rotatable element and means continuously engageable with said rotatable element for positively rotating the same in opposite directions.

2. Apparatus for controlling a refrigerating system having complementary heat exchange elements and a compressor comprising, in combination, valve means for interchanging the functions of said heat exchange elements while said compressor is inoperative, a switch mechanism rotatable about a single axis for establishing the pumping operation of said compressor automatically substantially upon completion of the interchanging operation, and means continuously engageable with said rotatable switch mechanism for effecting positive rotation of the same in opposite directions.

3. Apparatus for controlling a refrigerating system having complementary heat exchange elements and a compressor comprising, in combination, valve means for interchanging the functions of said heat exchange elements, a plurality of simultaneously rotatable switch contacts for rendering said compressor substantially inoperative automatically upon initiation of said interchanging operation and for establishing operativeness of the compressor substantially upon completion of said interchanging operation.

4. Apparatus for controlling a refrigerating system having complementary heat exchange elements and a compressor comprising, in combination, valve means for interchanging the

functions of said heat exchange elements, a plurality of mercury controlled contacts adapted to control operation of said compressor, and means for rotatably supporting and simultaneously actuating said contacts automatically in accordance with a predetermined operation of said interchanging valves.

5. Apparatus for controlling a refrigerating system having complementary heat exchange elements and a compressor comprising, in combination, valve means for interchanging the functions of said heat exchange elements, and means for controlling said compressor automatically in accordance with a predetermined operation of said interchanging mechanism including a plurality of rotatable mercury controlled switches having at all times a fixed angular relation with respect to each other so that in certain rotatable positions both contacts are broken and in other 20 positions one or the other of said contacts is completed.

6. Apparatus for controlling a refrigerating system having complementary heat exchange elements and a compressor comprising, in combination, valve means for interchanging the functions of said heat exchange elements, actuating means for said interchanging valve means, a mercury controlled switch for said compressor, and means for rotating said switch including movable and stationary cooperating members constantly engaged with each other and one of which is carried by and movable with said actuating means and the other of which is associated with a suitable stationary element.

35. 7. Apparatus for controlling a refrigerating system having complementary heat exchange elements and a compressor comprising in combination, valve means for interchanging the functions of said heat exchange elements, switch means for starting and stopping the compressor motor automatically upon initiation or completion of the interchanging operation including a pair of mercury switches disposed substantially at right angles to each other and with one 40 in a substantially horizontal position and the other in a substantially vertical position, when the compressor is operating and one of said heat exchange elements is functioning as a condenser, and vice versa when said heat exchange 45 element is functioning as an evaporator, and means for rotating said mercury switches automatically in accordance with actuation of said interchanging means.

8. Apparatus for controlling a refrigerating 50 system having complementary heat exchange ele-

ments and a compressor comprising, in combination, valve means for interchanging the functions of said heat exchange elements, nut and screw means for actuating said interchanging valve means, a rotatable mercury switch, a pivot pin for supporting said switch and carried by and movable with said nut, and stationary means for resisting movement of said switch, thereby causing the switch to rotate as said nut travels along the screw to effect said interchanging operation.

9. Apparatus for controlling a refrigerating system having complementary heat exchange elements and a compressor comprising, in combination, valve means for interchanging the functions of said heat exchange elements, and a plurality of rotatable switches for rendering said compressor inoperative automatically substantially upon initiation of said interchanging operation and of rendering the compressor operative substantially upon completion of said interchanging operation, said switches being supported for rotatable movement about a common axis.

10. Apparatus for controlling a refrigerating system having complementary heat exchange elements and a compressor comprising, in combination, valve means for interchanging the functions of said heat exchange elements, a plurality of rotatable switches for rendering said compressor inoperative automatically substantially upon initiation of said interchanging operation and of rendering the compressor operative substantially upon completion of said interchanging operation, said switches being supported for rotatable movement about a common axis, and means cooperating with said switches including an arm fixed to said switches for rotation thereof and a second pivot adapted for co-operation with said arm whereby relative movement between said two pivots effects rotation of 35 said switches.

11. Apparatus for controlling a refrigerating system having complementary heat exchange elements and a compressor comprising, in combination, valve means for interchanging the functions of said heat exchange elements, actuating means for said interchanging valve means, a mercury controlled switch for said compressor, and means for rotating said switch including movable and stationary cooperating members constantly 45 engaged with each other and one of which is movable with said actuating means and the other of which is associated with a suitable stationary element.

WILLIAM V. DUKE. 55
